FLEXIBLE TOY FIGURE

Irving Warhaftig, Livingston, N.J., assignor to Arrow Industries, Inc., East Paterson, N.J., a corporation of New Jersey

Filed Jan. 21, 1965, Ser. No. 83,517

Term of patent 14 years

(Cl. D34—4)

FIG. 1

I claim:

The ornamental design for a flexible toy figure, as shown and described.

EDWIN H. HUNTER, Primary Examiner.

JOEL STEARMAN, Examiner.
